(57) **CLAIM**

The ornamental design for a computing device display screen with graphical user interface for a food rating system, as shown and described.

DESCRIPTION

The sole FIGURE is a front view of the computing device display screen with graphical user interface for a food rating system showing the new design.

The outermost broken lines illustrate an electronic device and the remaining broken line illustrate the display screen and portions of the graphical user interface. None of the broken line form part of the claimed design.

1 Claim, 1 Drawing Sheet
